UNITED STATES PATENT OFFICE.

JOHN FRANKLIN JOHNSON, OF PORT DEPOSIT, MARYLAND.

FENCE.

No. 888,905.

Specification of Letters Patent.

Patented May 26, 1908.

Application filed March 7, 1908. Serial No. 419,789.

To all whom it may concern:

Be it known that I, JOHN FRANKLIN JOHNSON, a citizen of the United States, residing at Port Deposit, in the county of Cecil and State of Maryland, have invented a new and useful Fence, of which the following is a specification.

This invention relates to fences, wherein the upper and lower rails are made of channel iron and the pickets of iron rods.

The object of this invention is to provide an improved fence of the character described which may be readily shipped "knocked down" and set up without the aid of any skilled labor.

The invention consists in certain novel features of construction and arrangement of parts, hereinafter fully described, illustrated in the accompanying drawings, and specifically claimed.

In the accompanying drawings:—Figure 1 is a side elevation of the preferred form of the fence. Fig. 2 is a transverse section therethrough. Fig. 3 is a detail view of a portion of one of the channel irons. Fig. 4 is a vertical side elevation of another form of the fence. Fig. 5 is a top plan view of the second form. Fig. 6 is a view similar to Fig. 3, for use with the second form.

Similar numerals of reference are employed to indicate corresponding parts throughout the several figures of the drawings.

The numeral 10 indicates the fence post which may be made as here shown of a flat piece of bar metal, or, if desired, may be of ornamental cast iron.

Between each pair of posts extend channel irons 11 and 12, the channel iron 11 being that at the top, and that indicated by the numeral 12 at the bottom. Securely riveted, or otherwise fastened to these channel irons are angle clips 13, these clips being arranged on the under side of the irons by preference. Suitable openings are made in the fence post 10 and clips 13, being so arranged as to coincide when the channel irons 11 and 12 are in the desired position and bolts 14 are provided to hold the same together. In the channel iron 11 is formed a series of spaced openings 15, these openings in the preferred form being arranged along a median line and having semi-circular ends and flat sides, the length of the opening be-

ing somewhat less than twice its width. In 55 the channel iron 12 are formed a series of openings 16, circular in plan positioned to correspond with the openings 15 in the channel iron 11. Pickets are provided to extend through these openings. These pickets are 60 preferably of round bar iron, and are provided with a straight body portion, as indicated at 17, and reversely curved portion as shown at 18, this portion forming an offset of one half the diameter of the rod. A re- 65 turn bend 19 is formed beyond the reverse curve 18 and the outer end of the return bend is provided with a beveled point 20 adapted to fit the reverse bend 18 of the adjacent picket and a notch 21 on the side opposite of the bevel 20.

In the form of the device shown in Figs. 4, 5 and 6 there is simply a duplication of the elements shown in the other figures, and the purpose of this is to make a fence which shall 75 be closer than the preferred form. In order to accomplish this doubling, it is necessary that there be two series of openings 15 and 16 disposed in parallel lines on the channel web. Otherwise the device is the same.

It is to be observed that the channel iron 11 and end of the picket, as at 20, are so arranged that the end 20 will lie within the channel and thus prevent its being seen.

It is further to be observed in the construction by means of the reverse bend 18 the appearance of the fence is that of a single rod held between two bars with a split upper end.

In assembling the device all that it is necessary to do is to seat the posts 10 at a distance equal to the channels 11 and 12, bolt the channels thereto, and insert one of the pickets in the end holes of the channel, forcing the same down until the notch 21 engages the opening 15. The next picket is then inserted in the same manner, and so on to the end. At the end, however, it is preferred to secure the fence with a tightly fitting rod 22 with a simple straight body, as clearly shown in Fig. 1. There is thus provided a simple, ornamental, economical fence which may be shipped in pieces and readily assembled without the aid of any special skill.

It is to be observed that the fence as above described constitutes the principal element of the invention, but should it be desired to render the same more ornamental this may be done by the insertion of additional pickets

and a mid-rail or the like, as indicated at 23 in Fig. 1, and this latter may be made as ornamental as the occasion requires.

What is claimed is:—

5 1. In a fence of the character described, a picket formed of bar metal having a straight body portion, a **U** bend at the upper end thereof, said **U** bend being off set from the body portion by a reverse curve, the outer 10 end of the **U** bend being provided with a notch on the inner face thereof, and a bevel point formed on said **U** bend.

2. In a fence of the character described, posts, channel iron rails secured to said posts, 15 each provided with a series of spaced holes therein, a picket formed of bar metal having a straight body portion arranged to pass through the holes in the lower rail, a reverse bend adjacent the hole in the upper rail, a re- 20 turn bend above the upper rail provided in the outer end thereof with a bevel portion and a notch, said notch being arranged to engage the end of an opening in said upper rail and said bevel portion being arranged to bear 25 against the reverse bend of the adjacent picket.

3. In a fence, posts, channel iron rails detachably secured to said posts, said rails being each provided with a series of holes in the webs thereof, a series of pickets of bar metal 30 comprising a straight body portion extending below the top rail, a reverse bend lying within the limits of the flange of said top rail, a straight upwardly extending portion above said top rail being offset by the reverse bend 35 a distance equal to one half the width of said bar iron, a return bend above said last mentioned straight portion, a downwardly extending straight portion contacting with the upwardly extending portion of the adjacent 40 picket and provided with a bevel end to fit the reverse bend and a notch to engage the opening in the upper rail, said bevel end being held within the limits of the flange of said upper rail.

45 In testimony that I claim the foregoing as my own, I have hereto affixed my signature in the presence of two witnesses.

JOHN FRANKLIN JOHNSON.
